RELEASE TYPE TRIGGER MECHANISM

John H. Gartner, Kentfield, Calif., assignor to
Samuel I. Keene, San Francisco, Calif.

Application February 15, 1947, Serial No. 728,782

13 Claims. (Cl. 42—69)

1

This invention relates to trigger mechanisms for small arms, and has for one of its objects the provision of a trigger mechanism of the release type, which is the type in which the release of the cocking piece for firing is caused by releasing the retracted trigger, and which mechanism is under full control of the finger actuated trigger both for releasing the cocking piece and for preventing its release after a retraction thereof, as desired.

Another object of the invention is a trigger mechanism of the release type in which the cocking piece is safely held against accidental release up to the instant of its release, irrespective of the degree of manipulation of said trigger up to that instant.

A still further object of the invention is the provision of a release type trigger mechanism that operates to render a release of the trigger inoperative for releasing the cocked cocking piece upon a predetermined further movement of the trigger other than a release thereof and after the latter has been retracted to the point where its normal release would cause a release of the cocking piece. After such predetermined further movement, the trigger may be freely released without effecting a release of the cocking piece.

The merit of the release type of trigger mechanism has been recognized ever since it was first introduced, but for many years it was regarded as being merely a dangerous toy of no practical utility due to the fact that once the trigger was retracted its release without effecting a release of the cocking piece was practically impossible, particularly in a hammerless firearm or in a firearm having a bolt instead of a hammer.

In United States Letters Patents to Seitz, No. 2,365,440, of December 19, 1944, and No. 2,396,291, of March 12, 1946, safety means is provided in the form of an element adapted to be held by a finger or fingers of the hand grasping the stock. To release the trigger without effecting a release of the cocking piece, said finger or fingers released their grip on said element.

While the above means operated satisfactorily, the manipulation of the safety element required the actuation of a different set of muscles in the hand than those required for retracting and for releasing the trigger, and which muscles were not directly associated with the trigger finger. Thus the demand on the nervous and muscular system required to bring this second set of muscles into action while the set associated with the trigger finger was already in operation, was more complex than were the mental directive for ren-

dering the trigger safe applied mainly to the muscles already in operation, or at least to the muscles associated with the trigger finger.

In the present invention, after the cocking piece is cocked, all further physical manipulation either for releasing the cocking piece or for releasing the trigger without causing a release of said cocking piece, is by the trigger finger while the latter is in trigger retracting relationship. The result of this is an increased confidence on the part of the operator in the firearm through his having positive, simple and instant control of the cocking piece through the trigger alone.

Heretofore in most so-called bolt action firearms, or in those in which the cocking piece comprises a bolt, the latter carried a sear notch element that slidably engaged a sear for holding the cocking piece cocked. A release of the cocking piece was effected by sliding the sear off the sear notch element, and this sliding movement was a gradual one as the trigger was manipulated, until finally the sear cleared the element. If the trigger manipulation ceased and the trigger was restored to its normal inoperative position, a spring was provided for restoring the sear to its normal relationship with the sear notch element. However, this latter spring was resisted by the frictional resistance set up between the sear and the sear notch element by the much more powerful spring that drove the cocking piece once the latter was released, and as a result, the spring that was intended to restore the sear to full engagement with the sear notch element frequently failed to do so. Thus the sear many times would have only a hair breadth engagement with the sear notch element and only a slight jar would be sufficient to release the sear notch element and cause firing of the firearm. Such occurrences have not been infrequent, some of which have resulted in fatalities.

With the present invention, the sear engages the sear notch element exactly the same as in the conventional firearms, but the sear is not progressively slid off the sear notch element as the trigger is manipulated, nor is the release of the sear at the point of firing effected directly by manual force applied to the trigger. Instead, the trigger is retracted under a manual force of from three to four pounds, until a predetermined point is reached that is plainly evident to the operator's sense of feel on the trigger, and that may be audible. During this movement to said point, the sear is in substantially full, safe engagement with the sear notch element. However, upon release of the trigger at said point,

the cocking piece will be instantly released and the sear will actually be driven out of its holding relationship with the sear notch element under the force of the spring that drives the cocking piece.

From the foregoing it will be seen that there can be no dangerous "hanging" of the sear on the sear notch element under any circumstance.

The above described features of providing a safety control through the finger actuated trigger and a prevention of the dangerous "hanging" of the sear on the sear notch element are objects of this invention.

Other objects and advantages will appear in the description and in the drawings.

In the drawings,

Fig. 1 is a cross sectional view through a trigger mechanism showing the cocking piece in uncocked position.

Fig. 2 is a sectional view showing the cocking piece cocked and the trigger partially retracted in full line position to a point where a release thereof would result in a release of the cocking piece. The dash lines indicate the position of the trigger and sear before retraction of the trigger.

Fig. 3 is a sectional view showing the trigger fully retracted for causing a safety device to move to a position relative to the sear whereby the trigger can be released without causing a release of the cocking piece.

Fig. 4 is a perspective view of the sear.

Fig. 5 is a perspective view of the adapter that carries the sear between the arms of the former and that also carries the trigger.

Fig. 6 is a perspective view of a spring that functions to restore the sear to elevated position after the cocking piece has been fired.

Fig. 7 is a sectional view of the trigger mechanism in which the cocking piece is cocked but the trigger is held against retraction by an auxiliary safety device.

Fig. 8 is a sectional view of the trigger mechanism in which the cocking piece is in the forward position after having been driven by its spring to said position and the sear has been driven in rotation out of holding position. The dot dash lines of the trigger and sear and cocking piece indicate their positions just before the cocking piece has been released.

Fig. 9 is a sectional view showing the trigger mechanism with the cocking piece in uncocked position and the auxiliary safety device is engagement with the trigger preventing cocking of the firearm until said safety device is released.

Fig. 10 is an elevational view of the trigger alone as seen from one side thereof.

Fig. 11 is an edge view of the trigger of Fig. 10 as seen from the front or concave side of the finger engaging end of the trigger.

Fig. 12 is an elevational view of the trigger alone as seen from the side opposite that of Fig. 10.

Fig. 13 is an elevational view of the safety element carried by the trigger.

Fig. 14 is an edge view of the element of Fig. 13.

Fig. 15 is a horizontal fragmentary sectional view taken through the element of Fig. 13 and through the upper end of the trigger when said element is assembled with the trigger and is held in said relationship by a pin that is movable with said element between the two positions indicated by the dot-dash lines in Fig. 15.

Fig. 16 is a fragmentary perspective view looking at the trigger from below for showing the

canneleurs in the plate at the upper side of the trigger guard.

Fig. 17 is a sectional view of a trigger mechanism of slightly different design from that of Figs. 1 to 17 showing the cocking piece cocked and the trigger substantially fully retracted to the point where a release of the same will effect release of the cocking piece after a slight further retraction of the trigger.

Fig. 18 is a sectional view showing the trigger mechanism before retraction of the trigger and before the cocking piece is cocked.

Fig. 19 is a sectional view showing the finger engaging portion of the trigger moved upwardly so that the safety device carried at the upper end of the trigger will move to below a nose of the sear to permit a release of the trigger without causing a release of the cocking piece.

Fig. 20 is an exploded perspective view of the trigger of Figs. 17 to 19 apart from the firearm.

Fig. 21 is a vertical sectional view taken through the trigger of Fig. 20 when the latter is assembled.

Figure 22 is a perspective view of member 11 of the trigger mechanism.

In detail referring to Fig. 1, the bolt of the rifle is indicated at 1. The bolt so illustrated is the conventional bolt employed in the M1 Garand rifle and is constantly urged to fired position by the usual coil spring 2, which spring exerts a force of about 14 lbs. throughout its range of use.

The bolt 1 is reciprocable longitudinally thereof and conventional means (not shown) supports the same for reciprocation from cocked position (Fig. 3) at one extreme end of its stroke to fired position (Fig. 1) at the other end of said stroke.

Depending from the underside of bolt 1 and integral with the latter is a sear notch element 3 that is conventional in this type of firearm. This element 3 is more or less in the form of a tooth having a flat forwardly directed face 4 at right angles to the direction of travel of the bolt and element and an upwardly and rearwardly inclined face 5 extending from the outer end of the element to the bolt proper.

Bolt 1 and the element 3 thereon are disposed directly over the usual partition 6 that is between the bolt and the trigger mechanism, which partition forms the upper wall of the housing for said mechanism.

The partition 6 is formed with an opening 7 (Fig. 1) through which projects the nose 8 of a sear 9.

The main body of sear 9 is more or less horizontally elongated with said nose 8 projecting upwardly from a point intermediate its front and rear end portions.

In using the terms "front," "rear," "forward," "forwardly," "rearwardly," etc. the same are used with respect to the rear or butt end of the rifle and the forward or muzzle end thereof. Thus a rearwardly extending element extends generally toward the butt end and a forwardly extending element extends toward the muzzle end.

The rear end portion 10 of sear 9 terminates in a pair of laterally oppositely outwardly directed cylindrical projections 11 that extend into upwardly opening horizontally elongated similar recesses 12 formed in the upper edges of a pair of opposed horizontally directed arms 13 of a generally U-shaped member. The closed end of said U-shaped member is indicated at 14 (Fig. 5) and is at the forward end thereof while the edges of the arms at their free rear ends are curved as indicated in Fig. 1 to follow the downwardly curved contour of the partition 6.

The projections 11 form a support for sliding of sear 9 longitudinally of arms 13 and for pivotal movement of the sear about the horizontal axis of said projections upon actuation of the trigger as will later be explained more in detail.

Forwardly of sear 9 is the upper portion of a trigger 15, which upper portion extends between arms 13. A horizontal pin 16 extends through the said upper portion and into openings in arms 13 pivotally supporting said trigger for revolvable movement about the axis of said pin.

The portion of trigger 15 that projects downwardly from arms 13 terminates at its lower end in the conventional curved finger engaging portion 17 that projects through the floor plate 18 that is integral with the guard bow 19 for the trigger and that is at the upper end of said bow. The said portion 17 projects downwardly into the area or space enclosed within said guard bow for engagement by the finger of an operator in the usual manner.

The rear face of the upper portion of trigger 15 that is between arms 13 is formed with an upper notch providing an upwardly facing ledge 20 and a shoulder 21 spaced below said ledge 20 which shoulder 21 extends slantingly downwardly between vertical and horizontal (Figs. 1, 10, 12).

At this point it is thought that the structure will be clarified if it is pointed out that the upper portion of trigger 15 is flattened and its flat sides are parallel with a vertical plane that is coincident with the longitudinal axis of the rifle and between arms 13. This said upper portion is bifurcated in said plane (Fig. 11) and ledge 20 and shoulder 21 are respectively at both sides of said bifurcation.

The rear face of sear nose 8 is flat and is substantially vertical and is adapted to engage the forward side 4 of the sear notch element 3 when the bolt is in cocked position. The upper and forward face of said nose 8 is curved as indicated at 22 to facilitate the sliding of the inclined lower surface 5 of the sear notch element 3 rearwardly over said curved surface in cocking the bolt.

The forward side of the sear 9 is formed with a forwardly opening recess, the upper side of which starts at the lower end of conversely curved surface 25 that extend forwardly of curved surface 22, whereby the upper curved surface 25 and the upper side of said recess define two sides of an upper nose 23 (Fig. 4). The lower side of said recess defines the upper side of a lower nose 24, the lower side of which lower nose is the lower side of said sear. Said lower side is convexly curved from front to rear and the lower nose 24 is slightly longer than upper nose 23 and the upper side of lower nose 24 preferably extends slantingly downwardly toward the point of said lower nose.

When the firearm has been fired and the bolt is uncocked and trigger 17 is in forward position (Fig. 1) the upper nose 23 extends over the upper ledge 20 in the rear side of trigger 15 and the lower nose 24 extends over the lower shoulder 21 below ledge 20 with a slight space between the lower nose and said shoulder.

Forwardly of the upper portion of trigger 15 and between said upper portion and the forward end 14 of the U-shaped member is a block 26 that is preferably integral with the U-shaped member, and which block provides for certain screws as will later appear.

The partition 6 is formed with an opening over said block and the arms 13 are formed with opposed upward projections 27 that extend through

said opening. A pin 28 secures the projections to the partition, said pin being the conventional sear pin used in the standard rifle for pivotally supporting the conventional sear. The present structure substitutes the U-shaped member inclusive block 26 for the conventional sear and the pin 28 is merely used to hold the block in position.

A screw 29 extends through the block adjacent the end member 14 of the U-shaped frame and the lower end of said screw is slotted for a screwdriver.

The rear side of block 26 or the side adjacent the upper portion of trigger 15 is formed with a slot 30 (Fig. 5) that terminates at its lower end short of the lower side of the block 26 thus leaving a base 31 (Fig. 1) the underside of which is adapted to be engaged by a forwardly extending projection 32 on trigger 15 to function as a stop for limiting the forward swinging of the lower end of said trigger.

The forward end of slot 30 is vertical and terminates about even with the pin 28.

A vertically extending coil spring 33 is supported at its lower end on base 31 of slot 30 and a screw 35 threadedly extending through said base 31 carries a projection 34 that extends into the said spring, coaxial therewith for a substantial distance. The distance the projection 34 may extend into said spring is determined by screw 35, that projects below said base 31.

Positioned in the bifurcation of the upper end of the trigger 15 is a flat plate 36 (Figs. 13, 14). This plate 36 is formed with a short generally horizontally extending slot 38 that passes the pivot pin 16 that pivots the trigger.

Above pivot pin 16 the upper portion of trigger 15 is formed with two pairs of openings 46, 47 (Fig. 10), each pair being coaxial and extending through the opposite sides of the bifurcated position, thereby forming two pairs of opposed recesses in said sides (Fig. 15). Inasmuch as said trigger is of tempered steel, the said sides are resilient.

A pin 39 (Fig. 15) having hemispherical ends is fitted in an opening in the plate 36 and said ends are adapted to seat in one pair or the other of the opposed recesses provided by said openings. However, as will later be explained, a force in the plane of said plate 36 will cause the plate to move relative to the sides of the bifurcation for movement of the pin 39 from one pair of opposed recesses 46, 47 to the other and vice versa.

Said plate 36 is formed with a forward wedge-like extension 40 (Figs. 1, 13) that is tapered with its pointed end disposed between the upper end of spring 33 and partition 6. Said pointed end is also over the projection 34. Below said extension 40 is a shorter extension 41 (Fig. 13) that is substantially coincident with the projection 32 on trigger 15.

A pivot pin 44 that is spaced a substantial distance below the pin 16 pivotally supports the plate 36 on the trigger and in the bifurcation of the upper end of the latter.

The rear edge of plate 36 is formed with a projection 45, the upper edge of which is coincident with and alongside the upper edge of ledge 20 when the trigger is in the positions shown in Figs. 1, 2, 7, 8, 9 and in which positions the rear edge of said projection is coincident with the rear edge of the trigger that extends from ledge 20 to shoulder 21. In the positions shown in said figures it will be noted that the

pin 39 is seated at its ends in the forward pair of opposed recesses 46 (Fig. 15). Upon shifting of said pin to the other or rear pair of recesses 47 (Fig. 15) the projection 45 on plate 36 will project rearwardly of the rear edge 48 of the trigger and the upper edge of projection 45 will virtually form a continuation rearwardly of the upper edge of ledge 20 (Fig. 3).

The sear nose 8 is normally held elevated with the projections 11 spaced above the lower edges of recesses 12 in arms 13 by means of a plurality of thin spring leaves 50 (Fig. 6) that are secured at their rear edges to a cross piece 51 extending between the rear ends of arms 13. The rear edges of said leaves wipedly engage the underside of the forward projection 10 of the sear 9. The said springs 50 in piece 51 are seen in Fig. 6 separate from arms 13, and in Fig. 3 said springs are shown in position carried by said arms. In Figs. 1, 2 and 7 to 9 the springs 20 and cross piece 51 are not shown so as not to obscure the ends of arms 13, but on each instance the springs and cross piece are used.

Referring to Fig. 1 in which the bolt is in uncocked position, it will be seen that a retraction of the bolt to cocked position will cause the sear notch piece 3 to move over the sear nose 8, depressing the latter against the resistance of the spring leaves until the said piece 3 clears the nose; after which said sear nose 8 will move up 30 to hold the trigger cocked.

Upon retracting the trigger, the first action is that of causing the inclined shoulder 21 to engage the lower nose 24 on the forward side of the sear. Further retraction moves the sear rearwardly a short distance as seen in Fig. 2 and at the same time moving the upper nose 23 off the upper ledge 20. At this point a release of the trigger will result in the upper nose 23 engaging the rear edge 48 of the trigger adjacent the ledge 20 and the resistance to continued forward movement of the trigger by reason of this engagement would be a clear indication to the user that a further release of the trigger would cause a release of sear nose 8 from the sear notch piece 3 and that the firearm would be fired. Thus advance notice is very definitely given to the user as to the time when the cocking piece or bolt will be released.

The sensitivity of the trigger mechanism for releasing the bolt upon a further release of the trigger after the position in Fig. 2 is reached is determined by the degree of inclination of the shoulder 21 to the arc of travel of the lower nose 24 about the axis of the projections 11 of the sear. If this degree of inclination is close to being tangential to said arc, then the very slightest further release of the trigger will result in causing a release of the sear nose as best seen in Fig. 8. However, the more nearly the plane of said shoulder is to being radial to the arc of travel of the lower nose 24, the less sensitive will be the release.

Should the user decide not to fire the firearm after retracting the trigger to the position of Fig. 2, it will be seen that the sear nose 8 still fully engages the sear notch piece 3, hence there is no danger of firing the piece by a jar or the like; provided some means were provided for restoring the trigger to the position of Fig. 7 in which the bolt is merely cocked. Such means is provided for by the plate 36.

To restore the trigger mechanism to the position shown in Fig. 7, the operator will merely pull the trigger rearwardly to the maximum limit.

This requires a very noticeable extra exertion, hence such accidental retraction is practically impossible.

The result of this added retraction of the trigger is to cause a sliding of the sear rearwardly to the limit of the recess 12 and at the same time the wedge-like projection 40 on plate 36 will further compress spring 33 until the said projection 40 engages the projection 35 on screw 34. At this point a further retraction of the trigger will cause the pin 39 to be moved from holes 46 to the rear set of holes 47 resulting in a sharp audible snap and accelerated retraction of the trigger. Said movement of plate 36 upon the dislodgement of pin 39 will result in the rear projection 45 of plate 36 passing under the upper nose 23 of sear 9, thereby holding the sear nose up against releasing the bolt when the trigger is released. Fig. 3 shows the trigger fully retracted with the projection 45 on plate 36 projecting rearwardly under the upper nose 23.

Upon release of the trigger from the position seen in Fig. 3 the upper sear nose 23 will be guided back onto the upper ledge 20 and will be moved onto said ledge under the influence of the main bolt spring 2. The same spring will cause the plate 36 to move back to the position seen in Fig. 7 in which the pin 39 is back in recesses 46.

An added safety device is provided for holding the trigger against movement in either direction when the trigger is in the position indicated in Fig. 7. This device consists of a lever 55 that is pivoted at 56 to the base plate 18 at about the juncture between the forward side of the trigger bow 19 and the said base plate.

One arm 57 of this lever is formed with an upwardly directed tooth 58 at its outer end that is adapted to be swung into a downwardly opening recess 59 in the forward side of trigger 15 when the latter is in the position seen in Fig. 2. When the said tooth 58 is in said recess the opposite end of the lever is against the outer forward side of the trigger guard bow 19. Lever 55 is formed at its outer end with opposed side pieces 61 which extend past the trigger guard bow to a position in which a finger on the trigger can engage the edges of said side pieces and move the lever to a released position in which the tooth 58 is out of the recess or notch 59 as seen in Fig. 8. A pair of opposed detents 62 are formed on lever 55 that are adapted to spring past the guard bow 19 when the lever 55 is in "safety" position for holding the said lever from accidentally moving to "released" position. The position of the safety lever and its contour is seen to be such that it is practically impossible that the lever could be accidentally actuated to release the trigger and furthermore, the said safety lever is positioned for actuation by the trigger finger of the operator when said finger is in a position for engaging the trigger. It might also be added that the detents 62 function to prevent accidental return of the lever 55 to safety position, although it could not so return in any event after the trigger is slightly retracted.

As shown in Fig. 16, the upper side of the trigger guard or base plate 18 is formed with a plurality of parallel grooves 60 extending transversely of said plate and in a position directly over the trigger finger of the hand of a person when such finger is in trigger manipulating position. It is obvious that these grooves may be formed directly in said base plate, or in a plate 75 that is adapted to be secured to such base plate.

by one or more screws 64. The purpose of said grooves is to provide a friction surface adapted to be engaged by said trigger finger to facilitate holding the trigger in retracted position without causing undesirable nervous or muscular tension. When the trigger is retracted to the point where release thereof will result in firing the firearm, the operator may merely urge the trigger finger against the grooves and the friction surface created by the ridges will tend to hold the finger against movement in a trigger-releasing direction under a minimum expenditure of effort on the part of the operator. The spring 2 will tend to return the trigger to its forward position until the sear is released from engagement with the sear notch.

Figs. 17 to 19 inclusive, shows a modification of the invention as shown in the preceding drawings, and is substantially the same in its operation up to the point where an operation is required to prevent firing of the firearm upon releasing the retracted trigger. In the invention as described with respect to Figs. 1 to 16 inclusive, it was seen that an additional and final rearward pull of the trigger to substantially the limit of its maximum rearward movement rendered the cocked firearm safe for a release of the trigger. In the present instance, a further movement of the trigger beyond the point where a release of the same would cause a release of the sear is also necessary, but in this instance this further movement is in a direction substantially at right angles to the normal direction of movement of the trigger, preferably in an upward direction.

This modified form is recommended by some riflemen for the reason that it is possible for a person to fully retract the trigger accidentally in the excitement of the movement, which would prevent a release of the sear in the form of the invention as illustrated in Figs. 1 to 16 when no such result was intended.

With the present form of the invention, such an accidental occurrence is not likely inasmuch as a conscious upward and abnormal movement of the trigger would be required.

The same numerals will be used as for the invention as described in Figs. 1 to 16 where the elements in this invention are identical with those shown in said figures.

In detail, the bolt 1, spring 2, sear notch element 3, faces 4, 5 on said element, partition 6, sear 9 including all parts thereof, U-shaped member having arms 13, all are identical with corresponding elements shown in Figs. 1 to 16.

The trigger structure varies from that shown in the invention already described in certain features, but the upwardly facing ledge 20' and shoulder 21' spaced below said ledge are identical with the corresponding ledge and shoulder already described.

In the present invention, the upper portion 70 of the trigger is bifurcated substantially as already described, but in the space between the sides of said portion is a generally vertically extending flat, elongated member 71 (Fig. 22) pivoted to said trigger between said sides by a horizontal pivot 72 that is spaced below the pivot 16 that pivotally supports the trigger.

The lower end of this member 71 is formed with a rearwardly opening recess 69 (Fig. 22) that is adapted to receive the upper generally cylindrically shaped end 73 (Fig. 20) of the lower portion of the trigger, which lower portion includes the finger engaging part 74 at its lowermost end.

The trigger itself is in two parts, the upper part of which is formed with the ledge 20' and shoulder 21' that are identical with the ledge and shoulder shown in Figs. 1, 10 and that are for the same purpose.

The lower part 75 carries said cylindrically shaped end 73, and between said end 73 and the finger engaging portion 74 is a relatively straight neck 77 (Fig. 20) which neck 77 is gradually wider at its lower end and where it connects with the portion 74 as best seen at 78 in Fig. 20.

The lower end of the upper part 70 below pivot 72 extends to substantially the juncture between portions 74 and 78 and laterally overlies the upper portion of the lower part 75 from portion 78 upwardly, said parts 70, 75 being cut away at their overlying adjacent sides so that each of the opposite sides of the trigger from the portion 74 to the upper end of upper part 70 will be coplanar.

The adjacent sides of the overlapping portions of the upper and lower parts of the trigger are complementarily recessed to provide a chamber for an expansion coil spring 82 (Fig. 21). This spring reacts at its ends between a shoulder 81 on the part 75 and a shoulder 80 on part 70 to yieldably hold a stop 83 (Fig. 20) on part 75 against a shoulder 84 on part 70 in which position the parts 70, 75 are in normal extended position relative to each other. The neck 77 on part 75 is slidable longitudinally in a guideway formed in part 70 (Fig. 17) within the limits permitted by stop 83, said shoulder 84 being the limit at one end and a shoulder 85 being the other limit (Fig. 20). The guideway holds said neck 77 firmly therein except for longitudinal movement of the neck and corresponding movement of the finger engaging portion 76.

As already explained, the member 71 is adapted to pivot about the axis of pivot 72, and the socket 69 in the lower part of said member pivotally receives the cylindrical upper end 73 of part 75. The part 75 cannot become separated from the member 71 when the housing that encloses the trigger mechanism is together, and also the lower end of part 70 includes an extension 86 that fits in a slot in said lower part 75 (Fig. 21) to help hold the parts 70, 75 together.

The upper end of member 71 is formed with a notch 88 (Fig. 22) that corresponds with the notch at the upper rear corner of the part 70. The ledge 20' is the lower side of said notch in part 70, and when the trigger is normal, the sides of the notch 88 are coincident with the sides of the notch in part 70.

Upon upward movement of the lower part 75 against the compression of spring 80, the member 71 will rock on pivot 72 to swing the upper end of member 71 rearwardly to a position in which the upwardly facing lower side of notch 88 is substantially in outward continuation of the ledge 20'.

Forwardly of the upper end of the upper part of the trigger and between the sides 13 of the adapter that carries the sear 9, is the block 26 that has the projection 27 that in turn extends through an opening in partition 6, and which block is held in place adjacent closed end 14 by pin 28 that is the same pin that is shown in Fig. 1.

Spring 33 and screw 35 including extension 34 on said screen are the same as described for Fig. 1. The upper trigger member 70, however, carries a nose 90 integral therewith that extends over spring 33 and that functions to compress said spring when the trigger is retracted, where-

by the said spring will tend at all times to urge the trigger to a forward position.

In operation, after the firearm is cocked in the usual manner, and sear 8 and the sear nose 3 are in engagement, a substantially full retraction of the trigger to a slightly greater degree than the position shown in Fig. 17, will cause the upper nose 23 to move off ledge 20 and the lower sear nose to engage the shoulder 21.

When in such fully retracted position, if the trigger is released, the sear will quickly rotate counterclockwise under the force of spring 2 as soon as the lower nose 24 is no longer held on shoulder 21.

However, should the operator wish to release the trigger without firing the piece it is only necessary for him to move his trigger finger upwardly, thereby causing the member 71 to rock clockwise (as seen in Fig. 19), in which position the notch 88 will be swung outwardly so that its upwardly facing shoulder will be below the upper nose 23. Then upon releasing the trigger the upper nose 23 will be carried back over the upper ledge 20 and the firearm will be safely restored to normal cocked position without any relative movement having taken place between the sear 9 and sear nose 3.

I claim:

1. A firing mechanism for small firearms that includes a cocking piece and a spring energized by movement of said piece to cocked position for driving said cocking piece upon its release from said position, holding means supported for movement from a position holding said cocking piece cocked to a position releasing the same, means for causing said movement including a finger retractable trigger, means actuated by additional movement of said trigger after a predetermined retraction thereof for rendering said holding means inoperative for releasing said cocking piece, and means supporting said trigger for said predetermined retractive movement and for said additional movement.

2. A firing mechanism for small firearms that includes a cocking piece and a spring energized by movement of said piece to cocked position for driving said cocking piece upon its release from said position, holding means supported for movement from a position holding said cocking piece cocked to a position releasing the same, means for causing said movement including a finger retractable trigger, means actuated by additional movement of said trigger after a predetermined retraction thereof for rendering said holding means inoperative for releasing said cocking piece, and means supporting said trigger for said predetermined retractive movement and for said additional movement, said means for causing said movement of said holding means to a position releasing said cocking piece further including said spring.

3. A firing mechanism for small firearms that includes a cocking piece and a spring energized by movement of said piece to cocked position for driving said cocking piece upon its release from said position, holding means supported for movement from a position holding said cocking piece cocked to a position releasing the same, means for causing said movement including a finger retractable trigger, means actuated by additional movement of said trigger after a predetermined retraction thereof for rendering said holding means inoperative for releasing said cocking piece, and means supporting said trigger for said predetermined retractive movement and for said

additional movement, said holding means comprising a sear means supporting said sear for rotary movement under the influence of said spring from its holding position to a position fully releasing said cocking piece.

4. A firing mechanism for small firearms that includes a cocking piece and a spring energized by movement of said piece to cocked position for driving said cocking piece upon its release from said position, holding means supported for movement from a position holding said cocking piece cocked to a position releasing the same, means for causing said movement including a finger retractable trigger, means actuated by additional movement of said trigger after a predetermined retraction thereof for rendering said holding means inoperative for releasing said cocking piece, and means supporting said trigger for said predetermined retractive movement and for said additional movement, said cocking piece comprising a bolt supported for reciprocation and having a sear notch element rigid therewith adapted to be engaged by said holding means for holding by the latter, and said holding means comprising a sear supported for rotary movement to a position fully releasing said element for releasing said cocking piece.

5. A firing mechanism for small firearms that includes a cocking piece and a spring energized by movement of said piece to cocked position for driving said cocking piece upon its release from said position, a finger engaged trigger supported for rearward retractive movement to a predetermined point by the retractive force of the finger of an operator against said trigger and for opposite forward movement from said point upon release of said retractive force on said trigger, a sear notch element rigid on said cocking piece and a sear movable into and out of engagement with said element for respectively holding said cocking piece cocked and for releasing said cocking piece, means on said trigger for releasably holding said sear in said engagement with said element movable to a position releasing said sear from said engagement upon said opposite forward movement of said trigger, and safety means connected with said trigger and actuated for movement by a predetermined movement of said trigger to a position preventing said release of said sear from said element upon said forward movement of said trigger.

6. A firing mechanism for small firearms that includes a cocking piece and a spring energized by movement of said piece to cocked position for driving said cocking piece upon its release from said position, a finger engaged trigger supported for rearward retractive movement to a predetermined point by the retractive force of the finger of an operator against said trigger and for opposite forward movement from said point upon release of the retractive force on said trigger, a sear notch element rigid on said cocking piece and a sear movable into and out of engagement with said element for respectively holding said cocking piece cocked and for releasing said cocking piece, means on said trigger for releasably holding said sear in said engagement with said element movable to a position releasing said sear from said engagement upon said opposite forward movement of said trigger, and safety means connected with said trigger and actuated for movement by a predetermined movement of said trigger to a position preventing said release of said sear from said element upon said forward movement of said trigger, means supporting said sear for move-

ment out of engagement with said element under the influence of said spring.

7. A firing mechanism for small firearms that includes a cocking piece and a spring energized by movement of said piece to cocked position for driving said cocking piece upon its release from said position, a finger engaged trigger supported for rearward retractive movement to a predetermined point by the retractive force of the finger of an operator against said trigger and for opposite forward movement from said point upon release of the retractive force on said trigger, a sear notch element rigid on said cocking piece and a sear movable into and out of engagement with said element for respectively holding said cocking piece cocked and for releasing said cocking piece, means on said trigger for releasably holding said sear in said engagement with said element movable to a position releasing said sear from said engagement upon said opposite forward movement of said trigger, and safety means connected with said trigger and actuated for movement by a predetermined movement of said trigger to a position preventing said release of said sear from said element upon said forward movement of said trigger, means supporting said sear for rotary movement out of engagement with said element under the influence of said spring.

8. A firing mechanism for small firearms that includes a cocking piece and a spring energized by movement of said piece to cocked position for driving said cocking piece upon its release from said position, a finger engaged trigger supported for rearward retractive movement to a predetermined point by the retractive force of the finger of an operator against said trigger and for opposite forward movement from said point upon release of the retractive force on said trigger, a sear notch element rigid on said cocking piece and a sear movable into and out of engagement with said element for respectively holding said cocking piece cocked and for releasing said cocking piece, means on said trigger for releasably holding said sear in said engagement with said element movable to a position releasing said sear from said engagement upon said opposite forward movement of said trigger, and safety means connected with said trigger and actuated for movement by a predetermined movement of said trigger to a position preventing said release of said sear from said element upon said forward movement of said trigger, means supporting said sear for movement in translation upon said retractive movement of said trigger and for movement in rotation out of engagement with said element upon said forward movement of said trigger.

9. A firing mechanism for small firearms that includes a cocking piece and a spring energized by movement of said piece to cocked position for driving said cocking piece upon its release from said position, a finger retractable trigger supported for rearward retractive movement to a predetermined point by the retractive force of the finger of an operator against said trigger and for opposite forward movement from said point upon release of the retractive force on said trigger, holding means for said cocking piece supported for movement from a position holding said cocking piece cocked to a position releasing said cocking piece and actuated for said movement from said position by said forward movement of said trigger, safety means connected with said trigger and actuated by movement of said trigger

past said predetermined point for rendering said holding means inoperative for releasing said cocking piece upon said forward movement of said trigger, and means supporting said trigger for movement past said predetermined point.

10. A firing mechanism for small firearms that includes a cocking piece and a spring energized by movement of said piece to cocked position for driving said cocking piece upon its release from said position, a finger retractable trigger supported for rearward retractive movement to a predetermined point by the retractive force of the finger of an operator against said trigger and for opposite forward movement from said point upon release of the retractive force on said trigger, holding means for said cocking piece supported for movement from a position holding said cocking piece cocked to a position releasing said cocking piece and actuated for said movement from said position holding said cocking piece cocked to a position releasing said cocking piece and actuated for said movement from said position by said forward movement of said trigger, safety means connected with said trigger and actuated by movement of said trigger past said predetermined point for rendering said holding means inoperative for releasing said cocking piece upon said forward movement of said trigger, and means supporting said trigger for movement past said predetermined point, in a direction at an angle to said rearward retractive movement.

11. In a trigger mechanism having a spring urged cocking piece supported for movement under the influence of said spring from a cocked position to a released position, a finger retractable trigger and a sear connecting between said trigger and said cocking piece supported for movement under the influence of said trigger from a holding position holding said cocking piece cocked to a position releasing said cocking piece for said movement of the latter under the influence of said spring, said sear being actuated for releasing said cocking piece only upon movement of said trigger from a finger retracted position back to forward position and at a point in such movement, means for so causing said latter movement upon release of the retractable force on the trigger, and means actuated by a predetermined movement of said trigger other than a release thereof and after a retraction of said trigger to a predetermined distance for obstructing the release of said sear from said cocking piece upon a subsequent release of said trigger after such predetermined movement, said trigger being freely returnable to said forward position after said predetermined movement.

12. In a trigger mechanism having a spring urged cocking piece supported for movement under the influence of said spring from a cocked position to a released position, a finger retractable trigger and means connecting between said trigger and said cocking piece for releasably holding said cocking piece cocked including a sear actuated for movement to a position releasing said cocking piece by movement of said trigger from a finger retracted position back to forward position and at a point in said movement, means supporting said sear for said movement, and means engaging said sear for transmitting the power of said spring to said sear for positively driving said sear out of its holding position relative to said cocking piece and said point in the movement of said trigger, said cocking piece being of the reciprocable bolt type having a sear

15

notch element depending therefrom for engagement by said sear for so holding said cocking piece cocked, said sear being substantially stationary relative to said sear notch element during retraction of said trigger and return movement thereof to said point.

13. In a trigger mechanism having a spring urged cocking piece supported for movement under the influence of said spring from a cocked position to a released position, a finger retractable trigger and means connecting between said trigger and said cocking piece for releasably holding said cocking piece cocked including a sear actuated for movement to a position releasing said cocking piece by movement of said trigger from a finger retracted position back to forward position and at a point in said movement, means supporting said sear for said movement, and means engaging said sear for transmitting the power of said spring to said sear for positively

16

driving said sear out of its holding position relative to said cocking piece at said point in the movement of said trigger, a safety element connected with said trigger movable by a predetermined movement of the said trigger, after a retraction thereof and prior to movement of said trigger to said point, to a position, obstructing release of said sear upon subsequent movement of said trigger to said point whereby said trigger may be released after a retraction thereof without releasing said cocking piece.

JOHN H. GARTNER.
